IRONER SHOE OPERATING MECHANISM

Reuben J. McVey, Sandusky, Ohio, assignor, by
mesne assignments, to The Apex Electrical
Manufacturing Company, Cleveland, Ohio, a
corporation of Ohio

Application January 24, 1936, Serial No. 60,599

5 Claims. (Cl. 38—60)

This invention relates to ironers and particularly to those of the type which include an ironing roll, an ironing shoe movable to and from pressing engagement with the ironing roll, a clutch mechanism for operably connecting the roll with a power unit, and an operating mechanism for the shoe.

It is the principal object of the present invention to provide such an ironer with means for 10 coordinating operation of the ironing shoe with the clutch so that when the shoe is engaged with the ironing roll the clutch is operably connected with the power unit and when the shoe is moved out of pressing engagement with the roll 15 the clutch is disengaged, thereby enabling reduction of the ironer controls to a single lever mechanism.

Other important objects of the invention are to provide a coordinating connection capable of 20 free and easy operation with a minimum of sliding parts; to provide a coordinating means which is positively connected with the clutch mechanism and ironing shoe; and to provide an ironer construction which is readily manufactured with a minimum of machining operations.

25 In accomplishing these and other objects of the invention, as hereinafter pointed out, I have provided improved details of construction, the preferred form of which is illustrated in the accompanying drawings wherein:

30 Fig. 1 is a perspective view of a washing machine equipped with an ironer attachment embodying the features of the present invention.

Fig. 2 is an enlarged detail section through the 35 power end of the ironer, particularly illustrating the coordinating connections between the clutch and ironer shoe.

Fig. 3 is a similar view taken at substantially 40 right angles to the section illustrated in Fig. 2.

Fig. 4 is a section on the line 4—4 of Fig. 2, showing the ironing shoe disengaged from pressing contact with the ironing roll and the clutch yoke arm in position for retaining the clutch in disengagement with the actuating mechanism.

45 Fig. 5 is a similar view showing the parts in the position they assume when the shoe is engaged with the ironing roll.

Fig. 6 is a fragmentary plan view of the ironing 50 attachment particularly illustrating its hinge connection with the washing machine.

Fig. 7 is a fragmentary view partly in section to illustrate mounting of the ironer attachment on the housing of the wringer operating shaft.

55 Referring more in detail to the drawings:

I designates an ironer embodying the features of the present invention, and which for the sake of illustration is shown as an attachment for a conventional washing machine 2 including 60 a tub 3 that is mounted on a base 4 having legs

5 provided with casters 6 whereby the machine may be conveniently moved. Carried on the base 4, and operable by a suitable motor mounted under the base, is a transmission gearing enclosed in a housing 7 and extending upwardly therefrom 5 is a tubular post 8 enclosing a power shaft 9 for operating a wringer 10 as in conventional practice. The post 8 preferably includes upper and lower sections 11 and 12 between which is interposed a housing 13, including a vertically positioned cylindrical portion 14 forming a continuation of the post sections, and a horizontally arranged cylindrical portion 15 offset laterally from the side of the portion 14.

Located within the portion 14, and fixed on 15 the power shaft 9, is a worm 16 having meshing engagement with a worm gear 17 which is rotatably mounted in the portion 15 of the housing, the worm gear being mounted on a stub shaft 18 carried in a boss 19 of the housing. Fixed to and 20 forming a part of the worm gear 17 is a hub 20 having a clutch face 21 including spaced lugs 22 to be engaged by a similar clutch member 23 forming a part of the ironing mechanism, later described.

25 The side of the gear housing opposite the hub 20 is open, and inset therefrom is a washer 24 having its outer periphery seated against a shoulder 25 of the housing and having its inner periphery of sufficient diameter to freely engage 30 over the clutch face so that the lugs thereof project sufficiently to permit of their engagement with the clutch 23. The worm and worm gear are therefore enclosed so that they may be packed in a suitable lubricant. A similar washer 27, 35 spaced from the washer 24, engages the housing and the periphery of the clutch member 23 but without interfering with rotary and longitudinal movement of member 23.

Extending radially from the portion 14 of the 40 gear housing is an arm 26 to which the ironer is pivotally mounted as now described. The ironer proper includes a bracket 27 having a substantially cylindrical clutch housing portion 28 conforming in diameter to that of the cylindrical 45 portion 15 of the gear housing and which has a shouldered annular rim 29 for interengagement with an internal shoulder 30 in the gear housing whereby the clutch portion of the bracket is retained in concentric relation with the cylindrical portion 15. The bracket also includes a hub 31 extending in the opposite direction from the clutch housing to mount one end of a tubular sleeve 32 that constitutes a bearing support for an 50 ironing roll 33.

The ironing roll includes a cylinder 34 having closed ends 35 terminating in hubs 36 which have bearing openings accommodating the sleeve 32. The outer surface of the roller is covered by a 55

suitable padding material 37 as in conventional ironer roll construction.

Extending concentrically within the sleeve 32, and having driving connection with the outer end thereof, is a drive shaft 38, the inner end of which is rotatably mounted within and extends through a clutch actuating collar 39 having a hub portion 40 operably mounted within the open end of the sleeve 32, and a bell crank portion 41 located within the clutch housing. The shaft 38 extends into alignment with the clutch face 21 and mounts the clutch member 23 above referred to.

The clutch member 23 comprises a sleeve portion having a head 42 provided with lugs 43 adapted to interengage the lugs 22 of the other clutch member. The opposite end of the sleeve has slots 44 opening from the end thereof to pass the ends of a clutch pin 45 extending transversely through the shaft 38, and wherewith the clutch member is slidably keyed with the shaft so that when it is in driving relation with the lugs 22 of the other clutch member the shaft 38 is rotated to operate the ironer roll.

The clutch member 23 is normally urged into engagement with the clutch face 21 by means of a coil spring 46 having one end bearing against the bottom of a recess 47 of the collar 39 and its opposite end against the notched end of the clutch sleeve, as best shown in Figs. 2 and 3.

In order to move the clutch from engagement with the clutch face of the worm gear, the sleeve portion of the clutch 23 is provided with an annular groove 48 to receive the forked ends 49 of a clutch yoke 50. The clutch yoke 50 is pivotally mounted on a pin 51 projecting inwardly from the wall of the clutch housing, as best shown in Fig. 6.

The clutch yoke includes an arm 52 extending over the periphery of the clutch collar to be engaged by a cam lug 53 that is formed as an integral part of the collar 39. The collar 39 is oscillated to bring the cam 53 into engagement with the arm 52 of the clutch yoke by means of a lever arm 54 having one end threaded in a socket 55 of the collar and its opposite end extending through an arcuate slot 56 in the clutch housing to mount a handle 57. It is obvious that when the actuating lever 54 is moved in a clockwise direction, Fig. 5, the cam 53 engages under the arm 52 to rock the clutch yoke and effect retractive engagement of the clutch member 23 against action of its spring 46.

Extending radially from the clutch housing in substantial alignment with the clutch collar, and formed as a part of the bracket, is a hollow arm 58 carrying a bearing boss 59 that projects laterally thereof in spaced parallel relation with the ironing roller, as best illustrated in Fig. 6. The bearing boss 59 preferably aligns with an upward cylindrical extension of the hollow arm 58 to accommodate a rock lever 60 later described.

Fixed within an axial bore 61 of the boss 59 is one end of a sleeve 62, having its opposite end terminating substantially midway of the length 65 of the ironing roll. Rotatably mounted within the sleeve 62 and having its ends supported in bushings 63, is a rock shaft 64 having its ends projecting from the ends of the sleeve to respectively mount the rocker arm 60 and an arm 65 carrying an ironing shoe 66, as best shown in Figs. 1, 2 and 4. The arm 65 is preferably clampingly engaged with the end of the rock shaft 64, as indicated at 67.

The shoe 66 conforms in curvature and length 75 to that of the ironer roller and is heated by a

suitable electric heating element (not shown), that is supplied with current from a cord 68 leading from one of the electrical supply connections (not shown) of the washer. The shoe is preferably pivoted on the arm 65 by means of a pin 69 extending therethrough and through spaced ears 70 on the shoe. The shoe is thus mounted for rocking movement to and from pressing contact with the surface of the ironing roll, and I provide means for operably connecting the shoe 10 with the clutch collar so that when the clutch is thrown into driving engagement with the worm gear the shoe is moved into pressing contact with the surface of the ironing roll and when the clutch is disengaged through actuation of the 15 operating lever the shoe is moved away from the ironing roll, as now to be described.

In the device illustrated the rocker arm 60 is fixed to the shaft 64 by means of a pin 71 extending through a hub 72 thereof and through 20 the shaft. The arm extends downwardly from the hub into the hollow portion of the bracket and has pivotal connection by means of a pin 73 with a head 74 carried on a threaded rod 75 extending in the direction of the clutch collar. 25

Also formed as a part of the head 74, and projecting in the opposite direction from the rod, is a pin 76 forming a guide for retaining one end of a coil spring 77 in seating engagement with the head while its opposite end is seated over a 30 lug 78 projecting inwardly within the arm, as best shown in Fig. 4. The spring 76 has sufficient power to retain the shoe in disengaging relation with the ironer roll, as shown in Fig. 4, but is adapted to yield against power of a preponderating spring, later described, to permit engagement of the shoe with the surface of the ironing roll. 35

The threaded portion of the shaft is loosely mounted within one end of a sleeve-like rod 79 that has a head 80 fixed to its opposite end by a 40 pin 81 extending therethrough and through a shank 82 of the head which is engaged within the sleeve. The head 80 is pivotally eccentrically connected with the clutch collar by means of a pin 84, extending through an ear 83 on the collar, 45 as shown in Figs. 4 and 5. Telescoped over the sleeve 79 is a coil spring 85 having one end seating against the ear 83 and its opposite end seating on jamb nuts 86 adjustably mounted on the threaded portion of the rod to adjust tension of 50 the spring 85. It is thus obvious that when the lever arm is swung in an anticlockwise direction, Fig. 4, to move the cam lug from engagement with the clutch yoke, the ear 83 bears against the end of the coil spring 85 to compress the spring 55 against the jamb nuts 86, thereby moving the rod 76 against action of the spring 77 to rock the lever arm 72, and shaft 64, to effect swinging movement of the shoe into pressing contact with the surface of the ironing roll. 60

The spring 85 thus allows yielding movement of the head to and from engagement with the ironing surface for accommodating clothes of varying thickness incidental to telescoping relation of the rod 75 with the sleeve 79. When the lever 57 is released the spring 77 cooperates with the spring 85 to swing the actuating lever in a clockwise direction, lifting the shoe from pressing contact and causing the cam 53 to ride under the clutch yoke and effect disengagement of the 70 clutch from driving connection with the worm gear.

In order to mount the ironer attachment thus described so that it can be swung to and from the tub of the washing machine, the hollow ex- 75

5 tension arm of the bracket carries spaced ears 88 engaging the arm 26, and through which a hinge pin 89 is extended, as shown in Fig. 2. In order to retain the ironing attachment in fixed 10 relation with the gear housing, the clutch housing carries a suitable latch 90 that is pivotally mounted on an ear 91 projecting therefrom and which engages a lug 92 extending from the clutch housing, as best shown in Fig. 2.

10 In using the apparatus, and assuming that the ironer is pivoted to latched position with the gear housing, an article to be ironed is spread on the ironing roll 33 so that it lies flatly thereagainst with one edge in position to be engaged by the 15 ironing shoe 66.

The handle 57 of the operating lever is swung downwardly to rock the clutch collar 39 so that the spring 85 presses against the jamb nuts 86 to cause movement of the rod 75 and shifting of the 20 rock shaft 64 to move the ironing shoe into pressing position against tension of the spring 71. Simultaneously the cam 53 moves out of contact with the arm 52 to release the clutch yoke 50 whereupon the spring 46 moves the clutch 25 member 42 into engagement with the other clutch member 22 to cause rotation of the ironing roll. Movement of the roll feeds the article being ironed under the shoe. During this operation the rod 75 will reciprocate within its sleeve 79 to compensate for varying thickness of the article, the 30 spring 85 responding to maintain the desired pressure on the shoe. After the article has passed under the shoe the handle 57 is released to allow the springs 71 and 85 to expand and raise the shoe from contact with the roll. This action of the springs rocks the clutch collar to carry its cam under the arm of the clutch yoke to effect shift of the clutch member away from its mate to stop operation of the roll. The springs 85 35 and 71 normally retain the parts in the latter described positions. After use of the ironer the latch 90 may be released, whereupon the ironer is free to be swung on its pivot arm 89 back against the tub.

40 From the foregoing it is obvious that I have provided a simple, inexpensive ironer construction that may be readily assembled in the factory with a minimum of machining operations. It is also obvious that the ironer is readily operated when in use by means of a single control.

50 What I claim and desire to secure by Letters Patent is:

1. Ironer shoe operating mechanism including, 55 in combination with an ironing roll and clutch mechanism controlling operation of the ironing roll including a rockable throw member, an ironer shoe, a rock shaft mounting the shoe for movement toward and from the roll, a lever on the rock shaft, a two-piece pitman having one member thereof pivotally connected with said lever and its other member eccentrically mounted on said throw member and having yielding connection with the first member to compensate for variable movement of the ironer shoe relatively to the ironing roll, means for actuating the clutch throw member to shift the shoe in one direction, and resilient means acting directly on the lever for returning the shoe.

60 2. Ironer shoe operating mechanism including, 70 in combination with an ironing roll and clutch mechanism controlling operation of the ironing

roll including a rockable throw member, an ironer shoe, a rock shaft mounting the shoe for movement toward and from the roll, a lever on the rock shaft, a pitman including telescoping members, one eccentrically mounted on said throw member and the other pivotally connected with said lever, an adjustable stop on one of the pitman members, a compression spring surrounding the pitman and having one end engaging said stop and the opposite end engaging the other 10 pitman member, and a spring acting directly on said lever and its connected pitman member to urge the shoe from the roll.

3. Ironer shoe operating mechanism including, 15 in combination with an ironing roll and clutch mechanism controlling operation of the ironing roll including a rockable throw member, an ironer shoe, a rock shaft mounting the shoe for movement toward and from the roll, a lever on the rock shaft, a pitman including telescoping members pivotally connected respectively with the throw member and said lever, a stop member on one of the pitman members, a compression spring surrounding the pitman and having one end engaging said stop member and the opposite end 20 engaging the other pitman member, means for actuating said throw member in one direction to set the clutch mechanism and yielding rock the shoe toward the roll and in the opposite direction to release the clutch mechanism and pitman, 25 and resilient means for rocking the shoe away from the roll when the pitman is released.

4. Ironer shoe operating mechanism including, 30 in combination with an ironing roll and clutch mechanism controlling operation of the ironing roll including a rockable throw member, an ironer shoe, a rock shaft mounting the shoe for movement toward and from the roll, a lever on the rock shaft, a pitman including a tubular member having a head eccentrically, pivotally mounted on said throw member and a rod telescoping with the tubular member and having a head pivotally connected with said lever, an adjustable stop on said rod, a spring surrounding the pitman and engaging the head on the tubular member and the stop on said rod to yielding rock the shoe toward the roll in response to movement of the throw member in one direction, a spring engaging the head on said rod to automatically return the shoe in response to movement of the throw member in the opposite direction, and means for actuating the throw member.

5. Ironer shoe operating mechanism including, 55 in combination with an ironing roll and clutch mechanism controlling operation of the ironing roll including a rockable throw member, an ironer shoe, a rock shaft mounting the ironer shoe for movement toward and from the roll, a lever on the rock shaft, a two-piece pitman having one member pivotally connected with said lever and its other member eccentrically mounted on said throw member and having relative movement to the first member, a spring yielding engaged with the respective members of the pitman to yielding compensate for variable movement of the ironer shoe relatively to the ironing roll, means for actuating the clutch throw member to shift the ironing shoe in one direction, and resilient means acting directly on the lever for returning the shoe.

REUBEN J. McVEY. 70
